FRANK L. OHLER, OF TOLEDO, OHIO, ASSIGNOR TO THE HAUGHTON ELEVATOR AND MACHINE CO., OF TOLEDO, OHIO.

GATE-ACTUATING MECHANISM.

1,358,776.

Specification of Letters Patent. Patented Nov. 16, 1920.

Application filed August 25, 1915. Serial No. 47,216.

To all whom it may concern:

Be it known that I, FRANK L. OHLER, of Toledo, Lucas county, Ohio, a citizen of the United States of America, have invented 5 new and useful Gate-Actuating Mechanisms, of which the following is a specification.

This invention relates to actuating means for permitting or intercepting passage at a way.

10 This invention has utility when incorporated in doors or gates as in elevator cars and wells.

Referring to the drawings:

Figure 1 is a fragmentary section of an 15 elevator well, with a car therein, showing an embodiment of the invention;

Fig. 2 is a fragmentary detail of the door operating connector in disconnected position;

20 Fig. 3 shows the connector on a larger scale and in connecting position; and

Fig. 4 is a wiring diagram of the control connections as adapted to a three phase alternating electric current power supply.

25 The elevator well 1 has communicating therewith the different landings or ways 2 as closed by the doors or gates 3, vertically slideable in the guide 4.

Mounted for travel in the well 1 is the 30 elevator car 5 having connected thereto the operating device for the gates comprising the line 6 extending about the guide pulleys 7, 8, in the bottom of the well, thence up the well 1, over the pulley 9, under the fixed pulley 10, and over the movable pulley 11 reciprocable in the guide 12, mounted on the upper floor or landing 13. The line 6 in passing about the movable pulley 11 forms an adjustable bight which varies 35 the effective length of the line in its extension to the slack take-up connector 14 on the gate 15 traveling with the car 5. The gate 15 in its upward movement relatively to the car 5 for opening, is slideable in the 40 guides 16.

With the car 5 at a landing 2 and gates closed, the controller or switch 17 on the car 5 may be shifted to close the circuit with the line 18, for energizing the solenoid 19, as the circuit is completed through line 20, terminal 21 engaging the motor driven contact plate 22, passing therefrom through the contact or terminal 23, and in one of the circuits while the car is at rest line 24,

past switch 25 held closed by the cam plate 55 26 on the door 15 when closed. For completing the circuit in another phase of this three phase alternating current flow from the plate 22 would be by the line 43 to the line 44. If the door or gate 15 be open, the power 60 control circuit is broken. Thus there is energized the solenoid 27 to close the switch 28 thereby closing the circuit to the elevator operating motor power supply lines 29. Accordingly the elevator motor may be operated only when the gate is closed with the plate 22 in position for energizing the solenoid 27. This circuit from the coil 27 of the solenoid extends to the supply line 30. The supply line 31 has its circuit clear 70 through the coil or solenoid 32, so the circuit is completed to the switch 17. Shell 33 houses the coil 32.

Throwing of the solenoid 19 operates the reversible motor 34 for winding the drum 75 35 having attached thereto the line 36 extending over the pulley 37 for lifting the pulley 11 in the guide 12 for lengthening the bight in the line 6, thereby reducing the effective length of the line 6, and pulling 80 the gate 15 up, or to open position. This operation of the winding drum 35 carries with it the plate 22 which is mounted to rotate therewith, as shown in applicant's Patent 1,180,600 of Apr. 25, 1916. As the 85 gate 15 moves upward the switch 25 is opened, thereby breaking the circuit through the coil 27 and opening the switch 28 to cut out the driving motor for the car 5.

With the gate 15 fully open, for closing 90 the gate the switch 17 is moved to the position shown in Fig. 4, to connect the line 38, solenoid 39, line 40, terminal 41 contact plate 22, terminal 42, line 43 and supply line 44. As the plate 22 travels in the closing operation, it comes to position for connecting the line 24 in circuit in order that the solenoid 27 may be energized. This energizing of the solenoid may occur by completion of the circuit from the plate 22 100 in one phase, say by the line 43. Throwing of the solenoid 39 operates the motor 34 in the reverse direction from the operation by solenoid 19, and the drum 35 is driven to slack the line 36 and allow the pulley 11 105 to shorten the bight in the line 6, permitting the gate 15 to lower by gravity to closed position. The drum 35 has the line 45 ex-

tending past the pulley 46 to the counter-weight 47 to neutralize the weight of the operated parts and thus reduce the working load on the motor 34.

5 As thus described there is a power device connected to the car effective when the gate on the car is closed to open such gate and close the gate, independently of travel of the car.

10 For handling the gates at the well, the same device without additional control means is readily adapted. The switches 48 in the line 24 are maintained closed by the cams 49 on the several closed gates 3 grouped 15 in the well 1 for operation by the gate operating device. Accordingly throwing the switch 17 to the line 18 closes the circuit through the solenoid 19 for starting the motor 34. This energizing circuit through 20 the coil 32 in the shell or housing 33, attracts the armature 50 against the resistance of spring 51, and compresses the spring 52 to swing the arm 53 having the head 54 into the socket 55 of the gate 3 at the way or 25 landing at which the car 5 is stopped. Thus, when the motor 34 commences its drive, the gate 3 at such way or landing 2 is engaged for simultaneous shifting or opening with the car carried gate 15. If a gate 3 be open 30 this operation of the car by its power device may not occur, for the circuit in line 24 is broken.

With the two gates 3, 15 open, they may be readily closed by shifting the switch or controller 17 to line 38 to reverse the motor 34. The adjustable connector 14 permits maintenance of the gate sockets 55 in registry therewith at the landings, so the energized connector 50 through its head 54 may 40 properly engage. Upon deenergization, of coil 32, which occurs as the switch arm 17 is brought to central disconnected position, the spring 51 rocks the connector 50 away from the solenoid coil 32, and through the 45 bolt central of the spring 52 is effective to withdraw the head 54 from the socket 55 and there is no interference with the well gates 3 in any subsequent travel of the car 5 until a gate operation is desired and the 50 controller 17 moved to the line 18. The switch 17 for operating the gate 15 when released, breaks the circuit through the solenoid 19 and coil 32, and thus these operating coils use current only during the actual 55 travel of the gates, even though the gates may be left open at a landing.

In the event the gates 3 serve as fire doors or as safety guards against a stampede, the leaving of the gates open may be safely 60 guarded against by pivoting the head 54 on the connector arm 53, connecting at a mechanical advantage thereto the link 56 extending to a temperature releasable connection or fusible link 57.

65 The gate operating device herein is sim-

ple for installation in a wide range of wells or shafts with a minimum of special fittings, connections or operating parts, and may be adjusted readily for effective power control with interlocking checks not only against 70 movement of the car from a floor with the door or doors open, but against opening the doors away from a floor level, and against fire risk of leaving the doors open.

The cup of socket 55 holds the head 54 75 against release when coil 32 is deenergized and the gate load is on the head while with the gate load off the head 54 the spring 51 serves to disconnect the connector from the gate 3.

The moving of the doors by the power means when the car is away from the floor level is precluded by the switch 58 which is open to cut out circuit through the switch 17 except when the car 5 is adjacent a landing 2 when a cam 59 in the well will close the switch 58 on the car.

What is claimed and it is desired to secure by Letters Patent is:

1. An elevator car, a well therefor, having ways, a gate for a way, a gate operating device extending from the car to the gate and movable to operate the gate independently of car travel and driving means for the gate operating device as to which driving means the car may travel, there being a driving means control on the car for controlling said gate operating device. 90

2. An elevator car, a well therefor having a way, a gate for the way, and a gate operating device extending from the car to the gate, said device being provided with connections including a bight, a pulley in the bight, and means for moving the pulley in the bight for shifting the gate. 100

3. An elevator car, a gate carried thereby, power means controllable from the car as to which the car is movable, and connecting means from the power means to the gate and car. 105

4. An elevator car, a gate carried thereby, a power device for operating the gate, as to which the car is movable, and flexible means connecting the car and gate with which the power device may coact. 110

5. An elevator car, a well therefor having a way, a gate at the well for the way, a power device for operating the gate independently of car travel, and means connecting the gate and car with which the power device may coact. 120

6. An elevator car, a well therefor having a way, a gate carried by the car, a gate at the well for the way, a power device for operating the gates independently of car travel, and flexible means connecting the gate and car with which the device may coact. 125

7. An elevator car, a well therefor having a way, a gate carried by the car, a gate 130

at the well for the way, gate inter-engaging means movable independently of the gates for connecting the otherwise disconnected gates to each other for simultaneous shifting, and a power device for shifting one of the gates coacting through the means to actuate the other gate.

8. An elevator car, a well therefor having ways, gates for the ways and car, means extending between a first gate and the car, and a power gate operating device for shifting the gate independently of car travel by engaging said means intermediately of the extent of said means and moving the means and connection effecting means between the first and second gates controllable with said device for shifting the second gate with the first gate.

9. An elevator car, a well therefor having a way, a gate for the way, gate connecting means extending from the car, and a power gate operating device coacting with the means intermediately of the extent of the means and a solenoid controllable with the device to effect gate connection to the means for shifting of a gate.

10. An elevator car, a well therefor having a way, a gate for the way, gate connecting means extending from the car including a lifting connector for engaging the gate, a gate operating device engaging the means between the connector and car and connector actuating means controllable with the device to effect gate connection to the connector for shifting of the gate by the device.

11. An elevator car, a well therefor having a way, a gate for the way, and a device operable for opening the gate including a

temperature releasable connector for engaging the gate.

12. An elevator car, a well therefor having a way, a gate for the way, a gate operating device for shifting the gate independently of car travel, a connector traveling with the car for engaging the gate to connect the gate with the device, and driving means for the device as to which the car may travel.

13. An elevator car, a well therefor having a way, a gate for the way, a gate operating device connected to the car for shifting the gate independently of car travel, including a connector traveling with the car for engaging the gate, to connect the gate with the device, a controller on the car for the connector, and driving means for the device as to which the car may travel.

14. An elevator car, elevator operating power lines having a switch, a well for the car having ways, a gate carried by the car, gates for the ways, engaging means for the way gates movable relatively to the car and way gates, a gate operating power device coacting with the engaging means, and automatic lock-out means whereby an opened gate opens said switch.

15. An elevator car, a well therefor having ways, gates for the ways, and a gate operating device including a line connected to the car and extending therefrom to form a bight, and thence to connect to a gate, and a pulley movable in the bight to vary the effective length of the line and thereby shift the gate.

In testimony whereof I affix my signature.

FRANK L. OHLER.
